SUPPORT FOR TROUSERS

George W. Barnes, St. Louis Park, Minn.

Application September 18, 1933, Serial No. 689,915

1 Claim. (Cl. 2-237)

My invention relates to supports for trousers. Many persons do not wish to use suspenders and such persons have been accustomed to employ a belt to support the trousers. This belt passes through loop members disposed around the outer top portion of the trousers and is tightened by use of a buckle at the front. Such practice has the disadvantage of producing constriction across the abdomen of the wearer which is not only uncomfortable at times, but interferes with the circulatory system of the wearer. It is an object of my invention to overcome this disadvantage by providing supporting means which will not produce the constriction referred to but will permit the trousers to fit smoothly over the abdomen without any constricting effect over any particular portion. My device is not intended primarily as a substitute for the customary outside belt, but is preferably used in addition thereto, said belt being preferably employed for the sake of appearance but not as a supporter so that it is not necessary to impart any tightness thereto tending to produce the undesirable constriction previously referred to. In carrying out my invention, I provide elastic strap sections which are adapted to apply tension directly over the hips of the wearer. A further object of the invention is to provide means whereby the tension of the strap sections may be adjusted as desired. A still further object is to provide means whereby the elastic strap sections may be detached when the trousers are to be dry cleaned or washed.

The full objects and advantages of my invention will appear in connection with the detailed description thereof, and the novel features of my inventive idea will be particularly pointed out in the claim.

In the accompanying drawing which illustrates a practical embodiment of my invention:— Fig. 1 is a perspective view of a pair of trousers embodying the invention, the view being taken substantially from the front.

Fig. 2 is a fragmentary elevational view on an enlarged scale showing the device as applied to one of the hip portions of the trousers.

Fig. 3 is a top plan view of what is shown in Fig. 2.

Fig. 4 is an elevational view showing the parts of the device in separated condition.

Fig. 5 is a top plan view of what is shown in the left hand portion of Fig. 4.

Referring to the particular construction shown in the drawing, the numeral 10 designates in general a pair of trousers provided with the customary belt 12. One of my devices is applied to

each of the hip portions of the trousers and, therefore a detailed description of one of them will be sufficient for a full understanding of the invention. A piece of non-elastic material 14 is secured as by sewing inside the top portion of the trousers immediately at the rear of the hip portion. A set of fastener members 16 is carried by the piece 14, these fastener members as shown being stud members of well known snap fasteners. In the embodiment shown, the term "set" applies to 2 fastener members, but it will be understood as a matter of course that a single fastener member might be used although not as effectively. Therefore the term "set" wherever used in connection with fastener members is intended to refer to any desired number of such members.

A piece of non-elastic material 18 is secured as by sewing inside the top portion of the trousers immediately at the front of the hip portion. Sets 75 of fastener members 20, 22, 24 and 26 are carried by the piece 18, these fastener members shown being stud members of well known snap fasteners.

I provide an elastic strap section 28, to the rear end of which a piece of non-elastic material 30 is secured. A set of fastener members 32 is carried by the piece 14, these fastener members being socket members adapted to cooperate detachably with the stud members 16. A piece of non-elastic material 34 is secured to the front of the section 28 and the piece 34 carries a set of fastener members 36. The members 36 are socket members and are adapted to cooperate detachably and interchangeably with the sets 20, 22, 24 and 26.

The elastic strap section 28 is preferably of greater width than the pieces of non-elastic material 14 and 18, the pieces of non-elastic material 30 and 34 being of the same width at their attached ends as the section 28 and tapering by double curved edges as indicated at 38 and 40 respectively to the width of the pieces 14 and 18. The edges 38 and 40 provide for a snug fit upon the hips of the wearer. It will be noted that the non-elastic piece 34 has its free end extending sufficiently to form a flap for covering the sets of fastener members 22, 24 and 26 when any one of these sets is engaged by the fasteners 36.

The operation and advantages of my invention will be readily understood in connection with the foregoing description and the accompanying drawing. The set of fastener members 20 correspond to a neutral condition of the elastic section 28 since the latter will not be placed under tension when the fastener members are engaged therewith. In applying the device to the trou-

sers, the members 36 are engaged with the members 20, and with the elastic section 28 lying smoothly on the trousers, the non-elastic pieces 14 and 18 are secured in place. Thereafter when 5 it is desired to support the trousers from the hips, the members 36 may be engaged either with the members 22, 24 or 26, depending upon the amount of tension which it is desired to apply over the hips of the wearer. The use of my device results 10 in the elimination of constriction over the abdomen of the wearer even when a rigid belt is employed for the sake of appearance since this belt is not pulled tight. When the wearer bends over, the elastic section will stretch still further since 15 ordinarily there is some reserve in the elastic section. On the other hand if a rigid belt is relied upon to hold up the trousers, an additional constriction is imposed over the abdomen.

I claim:

20 A support for trousers comprising a piece of non-elastic material secured inside the top portion of the trousers immediately at the rear of the hip portion, a set of fastener members carried by said piece, a piece of non-elastic material se- 25

cured inside the top portion of the trousers immediately at the front of the hip portion, sets of fastener members carried by said piece, an inside undivided elastic strap section, the first of said sets corresponding to a neutral condition of said section and the remainder of said sets corresponding to successive tensioning condition of said section, a piece of non-elastic material secured to the rear of said elastic section, fastener members carried by said piece adapted to cooperate detachably with said first mentioned fastener members, a piece of non-elastic material secured to the front of said elastic section, and fastener members carried by said piece adapted to cooperate detachably and interchangeably with said sets of fastener members whereby said elastic section may be placed in neutral condition and may be placed in successive tensioning condition over the hip of the wearer, said last mentioned piece of non-elastic material having its free end extending sufficiently to form a flap for covering said sets of fastener members for all of the tensioning positions of said elastic section.

GEORGE W. BARNES.
